CLAIM

The ornamental design for a mirror, as shown and described.

DESCRIPTION

FIG. 1 is a front left perspective view of a mirror of our new
design;

FIG. 2 is a front elevation view thereof, the rear being plain
and unadorned;

FIG. 3 is a side view thereof, the opposite side being a mirror
image of the side shown;

FIG. 4 is an enlarged partial view of the upper left hand and
central portion of the mirror of our design; and,

FIG. 5 is an enlarged partial view of the lower left hand and
central portion of the mirror of our design.
